UNITED STATES PATENT OFFICE.

PAUL E. SCHLEICHER, OF GARY, INDIANA, ASSIGNOR TO SCHLEICHER, INC., OF CHICAGO, ILLINOIS, A CORPORATION OF ILLINOIS.

RADIATOR COVER.

Application filed June 13, 1925. Serial No. 36,998.

This invention relates to a radiator hood of that type which enclose the radiator upon all sides as well as the top.

It is an object of this invention to provide a frame with novel attaching means whereby a variety of different panels may be supported.

It is a further object of this invention to provide such a structure in which the parts 10 can be readily alined and drawn together in proper alinement to provide a secure and tight joint.

With these and other objects in view which will become more apparent in the following description and disclosures, this invention comprises the novel structure and combinations hereinafter described and more particularly pointed out and defined in the appended claims.

20 In the accompanying drawings which illustrate a preferred embodiment of this invention and in which similar reference numerals refer to similar features in the different views:

25 Figure 1 is a side elevational view of a radiator cover involving this invention.

Figure 2 is an end elevational view of the same.

30 Figure 3 is an enlarged vertical longitudinal sectional view of the same.

Figure 4 is an enlarged fragmentary interior view partly in section illustrating certain details.

35 Figure 5 is an enlarged fragmentary interior view partly in section illustrating certain features.

Figure 6 is an enlarged sectional view through a corner of the radiator cover illustrating the alining and attaching mechanism.

40 Figure 7 is an enlarged fragmentary sectional view upon the line VII—VII of Figure 1.

Figure 8 is an enlarged fragmentary plan view of the alining and clamping means on the rear post.

45 Figure 9 is an enlarged fragmentary part sectional and part elevational view of one of the legs of the frame.

50 Figure 10 is an elevational view of a modified form of radiator cover.

Figure 11 is an enlarged sectional view upon the line XI—XI of Figure 10.

Figure 12 is an enlarged fragmentary in-

terior plan view of one side illustrating certain features.

Figure 13 is an enlarged fragmentary sectional view taken substantially upon the line XIII—XIII of Figure 2.

Figure 14 is an enlarged sectional view 60 taken substantially upon the line XIV—XIV of Figure 13.

Figure 15 is a fragmentary elevational view of a radiator cover having a modified form of panel.

Figure 16 is an enlarged sectional view taken upon the line XVI—XVI of Figure 15.

Figure 17 is an enlarged fragmentary top plan view of the modified panel shown in 70 Figure 15.

Figure 18 is a fragmentary sectional view upon the line XVIII—XVIII of Figure 17.

Referring now to Figures 1 to 9 and 15 75 and 16 of the drawings, which illustrate a four post radiator cover, it will be observed that said hood comprises a rectangular frame, the sides and ends of which are closed by separate panels.

The frame comprises a pair of front posts 1, which are connected by an upper member 2 and a lower member 3 whereby an open space is provided for a perforated metal panel 4 which may be like a cane bottom 85 seat as shown in Figures 1 and 2 or may be in the form of a grid as shown in Figure 15. The frame further comprises a pair of rear posts 5. Each rear post is connected to a front post by an upper transverse member 6 and a lower transverse member 7. These posts are in the form of right angled members as shown in cross section in Figure 6. The upper and lower portions of the flanges are turned at right angles, as indicated at 8, with the exception of the rear flanges on the rear posts, which are flat for the purpose of affording means for attaching a rear metal panel 9, as shown in Figure 3. A small angle clip 10 (Figure 9) is 95 secured to the lower end of each post and a foot 11 is attached to each angle clip.

Both flanges of the two front posts and the forwardly extending flange of each of the two rear posts between the inturned lip 105 8 are provided with inwardly offset seats 12 (Figure 13). The upper and lower rail members 2, 6, 3 and 7 are likewise provided

with inwardly offset seats 12. These seats are formed by bending the metal inwardly at right angles to provide a proper depth of offset and then bending the same at right angles again whereby a part of rabbet is formed for a purpose that will later appear.

The posts are connected with the different rail member 2, 3, 6 and 7 by novel forms of alining and clamping means that will now be described. The structure of the alining and clamping means in connection with the front posts are best shown in Figures 4, 6 and 7. Each front post has an upper and lower alining and clamping member which are similar in structure. Each member consists of a right angled channel shaped metal device 13 secured to suitable filler pieces 14 attached to the interior of the post. The ends of each member project beyond the post to which it is attached and terminate in suitable apertured lugs 15 which extend inwardly at right angles to the base of the device.

Each of the rear posts 5 has an upper and lower alining and clamping member 16 such as is shown in Figure 8. Each clamping member consists of a channel shaped device that only projects beyond the forward edge of the post, and adjacent the projecting end of the device there rises a lug 15 having a threaded aperture.

Each of the ends of the upper and lower rails 2, 3, 6 and 7 is provided with an alining and clamping means in the form of spaced parallel Z bars 17 welded to a base 18 which is secured to a rail. These Z bars are so spaced and the webs are so proportioned that the outstanding flanges 17 which are directed toward each other take over the flanges of a channel 13 whereby a guideway is formed for receiving the projecting ends of the channel clamping members 13 on the post. Each base 18 is provided with an upstanding apertured lug 19 at its rear end that abuts the rear ends of the Z bars. A screw 20 extends through this lug and is threaded in a lug 15.

It will be obvious that in assembling the frame, the alining members are brought into telescopic relation with the alining means on the rails, the screws 20 inserted through the lugs 19 and screwed into the lugs 15. This will draw the ends of the rails tightly against the lips 8 of the posts. It will be evident that if the alining and clamping members are properly positioned, the posts and rails will be drawn together with their outer surfaces flush.

Suitable panels fit in the offset seats in the front and ends of the frame and are clamped therein by moulding strips 21 and 22 and 23. These mouldings are similar in cross section. They merely differ in length. Each moulding strip is stamped or formed from suitable metal into a hollow triangular

shape having a base and side that fit against the walls of the offset seat 12. The metal that connects the base is curved to provide an ornamental design such as is common in mouldings. The lower end of the side and the inner end of the base are spaced apart to provide a slot into which screws 24 may be passed for attaching the same in the seat 12. These screws have flat shanks as shown in Figure 14, and conical heads that fit against the inner side and base of the moulding. The screws may be slid in from one end of the moulding. Suitable apertures are provided in the corners of the right angled seats 12 for receiving the screws 24. Angle clips 25 serving the purpose of washers are shaped to fit the interior corners of the seats 12. These angle clips 25 are provided with terminal feet 26 that add rigidity thereto.

The front rail 2 is interiorly folded upon itself at its upper margin as shown in Figure 5, and the depending fold has a horizontally extending flange 27 which forms a seat for a humidor 28.

In some cases, it may be desirable to use a longer radiator hood requiring a central front post. In Figures 10, 11 and 12 there is illustrated such a structure. This central post consists of a vertical channel shaped member 29 having a pair of diverging angle bars 30 and 31 with overlapping base flanges to which a post 32 is secured.

An upper and lower alining and clamping device 33 is secured to the post for attachment to the rails 2 and 3. The form of clamping device is best shown in Figure 12. It consists of a channel shaped member that projects beyond the sides of the post with a lug 15 adjacent each end. The ends of the rails 2 and 3 have alining and clamping means 17, 19 and 20 similar to those heretofore described that telescope over the projecting ends of the channel members 33. Otherwise this structure is similar to the one previously described.

A cover 34 fits over the top of the frame for closing the same. The humidor 28 is suspended just below this cover, one side thereof resting upon the aforementioned flange 27, and the other side being suspended by hooks 35 that engage over the sheet metal panel 9 as shown in my copending application for Patent No. 722,974.

In Figures 15 to 18, there is illustrated a radiator hood comprising a frame similar to the one previously described. The only difference between this structure and that of Figure 1 resides in a different form of panel. In this modified form of panel, a pair of rods 36 support alternately long and short grid bars 37 and 38 which are spaced from each other by suitable sleeves 39 on the rods. The upper and lower ends of the long grid bars are clamped between the rails and

the moulding 21 as shown in Figure 16. Only the lower ends of the short grids are thuswise clamped. The ends of the bars 36 are clamped between the posts and mouldings.

The cover 34 which is the same in all cases, has an inlet door 40 (Figure 3) for pouring fluid into the humidior, and one end of the hood is provided with a door 41 (Figure 2) for access to the valve of the radiator.

It will be appreciated that the frames may be readily constructed to fit any suitable radiator and may contain various forms of panels which may be removed and replaced by others. It will also be appreciated that the novel form of alining and clamping means will properly unite the parts and maintain the same in rigid relation. Further the concealment of the heads of the screws 24 in the hollow moulding increases the appearance of the hood without in any way weakening the structure.

I am aware that many changes may be made, and numerous details of construction may be varied through a wide range without departing from the principles of this invention, and I therefore do not purpose limiting the patent granted hereon, otherwise than necessitated by the prior art.

30 I claim as my invention:

1. In a radiator hood, a frame comprising posts and connecting rails, said rails and posts having inwardly offset seats, panels supported in said seats, hollow mouldings fitting said seats for confining said panels in said seats and means for securing said moulding to said frame, parts of said means being concealed in said mouldings.

2. In a radiator hood, a frame comprising posts and connecting rails, said rails and posts having inwardly offset seats, panels in said seats, hollow moulding strips abutting the margins of said panels, and bolts having their heads concealed in said hollow mouldings and extending through said seats for removably confining the panels in position.

3. In a radiator hood, a frame comprising a plurality of posts, upper and lower rails connecting a pair of said posts, said rails and last-mentioned posts having inwardly offset seats, a panel in said seats, hollow

moulding members extending along the outer margins of said seats, and attaching means 55 slideable lengthwise into said moulding members and concealed thereby.

4. In a radiator hood, a frame comprising a plurality of posts, a pair of said posts having channel shaped alining members, a pair of rails between said posts, having alining means in telescopic relation with said channel shaped members, means for adjustably connecting said means and members, said posts and rails having inwardly offset seats and a panel confined in said seat.

5. In a radiator hood, a frame comprising a plurality of posts, a pair of spaced rails connecting a pair of said posts, a panel abutting said rails and last-mentioned posts, hollow moulding members extending along the margins of said panels, and headed securing means for attaching said moulding members, with the heads thereof concealed in said hollow moulding members.

6. In a radiator hood, a frame comprising 75 a plurality of posts, each post having laterally projecting channel shaped members provided with lugs, rails having means in telescopic relation with said channel shaped members, and having lugs and screws 80 extending through lugs on said means and members for drawing said posts and rails together.

7. In a radiator hood, a frame having inwardly offset margins, a panel seated against 85 said margins, hollow moulding members extending along the margins of said panel and attaching means for said members extending through said frame and into said hollow members and concealed thereby.

8. In a radiator hood, a frame comprising a plurality of posts, a pair of said posts having upper and lower inturned lips and intermediate offset seats, a rail extending between each pair of lips, said pair of posts and rails having telescopic alining and clamping means, said rails having offset seats, a panel abutting the seats of said posts and rails, and means for removably confining said panel.

100 In testimony whereof I have hereunto subscribed my name.

PAUL E. SCHLEICHER.
